MAGAZINE FOR LEAD PENCILS

August Leistenschneider, Dusseldorf, Germany

Application January 29, 1934, Serial No. 708,802
In Germany January 31, 1933

8 Claims. (Cl. 120—22)

This invention relates to a magazine for mechanical or magazine lead pencils, in which the projection of the leads is effected by means of pressure brought to bear upon the pencil cap. In such pencils the lead reposes in a magazine, from which it is led into a guiding-tube within the middle part of the pencil sleeve. From there it enters into the front part of the pencil, containing the lead-projecting device.

According to experience, in mechanical pencils of this type the introduction of the leads from the magazine into the guiding-tube within the middle part of the pencil tube presents peculiar difficulties, since during this introduction jamming, e. g. by the crossing of the leads, etc., easily occurs. The leads are disposed side by side in large numbers under the pencil-cap. They are therefore easily jammed during their introduction into the filling-tube. This jamming, strangely enough, takes place, as the inventor observed, when the bottom of the magazine is funnel-shaped with a very steep surface, although this form was intended to facilitate the introduction of the leads. According to this invention, the introduction of the leads from the magazine into the guiding-tube is facilitated by transmitting the movement of the pencil-cap to the leads by means of special parts moving together with the cap. These parts touching the leads may be of different types and shapes, and may move in various ways. The magazine-walls or magazine-bottom may for instance be movable, e. g. turnable, or the movement may be effected by means of other organs e. g. resilient parts introduced into the magazine-space when the cap moves. Furthermore the lead-bottom itself can e. g. be jointed flexibly with the cap or can be formed flexibly so that by the movements of the cap it changes its form.

The end of the filling-tube may also be shaped shovel-like or screw-shaped and extend a little through the lead-bottom into the magazine. It may also be arranged movably with respect to the lead-bottom in such a manner that it enters into the lead-space by pushing the lead-bottom. In this case the shovel-like end of the filling-tube forms the connecting-part between the magazine and the filling-tube, and acts upon the leads.

The movement of the magazine-bottom, or of the filling-tube, or of both, may be limited by suitable projections.

In the accompanying drawing several ways are shown in which the invention may be constructed. Fig. 1 shows a mechanical lead pencil with the

new mechanism according to the invention in longitudinal section.

Fig. 2 shows the magazine constructed according to Fig. 1, when the pencil-cap is pressed downwards.

Fig. 3 shows a modified construction of the magazine in longitudinal section.

Fig. 4 shows a section on the line A—B in Fig. 3.

Fig. 5 shows a further form of construction of the magazine.

Fig. 6 shows a section on the line C—D in Fig. 5.

Fig. 7 shows the construction of the magazine according to Fig. 5 when the pencil-cap is pressed downwards.

Fig. 8 shows a further form of construction of the magazine and of the mechanism for the introduction of the leads into the filling-tube.

Referring to the drawing: In Fig. 1, '1 refers to the case or outer surface of the pencil, which may be made from a variety of materials, e. g. metal, vulcanite, or an artificial mass. In this shaft 1 is fixed a tube 2, into which is slidably guided a sleeve 3 for the reception of the pencil leads 4. On the sleeve 3 is screwed, e. g., a nut 5, into which nut is screwed a closing-piece 6, 25 with a grasping-cap 7. With the sleeve 3 is connected a ring-shaped part 8, whose upper funnel-shaped surface 10 forms the bottom of the lead-magazine. To the ring-body 8 is joined the filling-tube 11, into which the leads 4 are introduced 30 from the magazine-space. According to Fig. 1 the lead 4 has e. g. only its smaller end in the magazine-space, while the larger part is already in the filling-tube 11. The lead 4" is already 35 completely in the filling-tube, and the lead 4''' in the foremost part of the filling-tube, in the so-called clamping-device 12. The foremost end of the lead 4''' is appearing through the opening 13 of the pencil point 14, so that the pencil is ready for writing.

The propelling mechanism may be of a very varied nature. In the above-described case it consists of a spring 15, one end of which rests upon the ring-shaped body 8, while the other end of this spring rests on the ring 16, which is firmly 45 fastened to the point-casing 14. To effect the propelling of the leads there is also arranged upon the conically shaped part 17 of the clamping-device directed towards the pencil-cap, a loose ring 18, which when the filling-tube 11 and the 50 clamping-device 12, 17 are pushed forward, moves forward with them until it strikes against the projection 19 arranged within the point-casing. The foremost part of the clamping-device 12 is furthermore provided with slots 20, so that at its 55

front end separate resilient cheeks are formed.

The propelling of the leads in such a mechanical or magazine pencil is effected in such a manner that pressure is exercised on the caps 6, 7 in the direction of the arrow, and the cap is brought into the position seen in Fig. 2. The pencil case 3, together with the ring-body 8 and the filling-tube 11, is also pushed towards the pencil-point as shown in Fig. 2. By this movement a correspondingly longer portion of the lead 4''' is projected at the same time from the point 14. The spring 15 is by this forward movement pressed together. When the cap 6 has been freed the pressure of the spring 15 guides the case 11 and the magazine-body 3 with the cap 6 automatically into the original position shown in Fig. 1.

Furthermore, through the propelling movement the conically shaped part 17 carries forward the ring 18 lying upon it until the ring 18 is resting on the notch 19 and its movement thus checked. When the case 11 with the parts 12, 17 now moves farther towards the point, the clamping exercised by the ring 18 on the cheeks of the foremost part 12 of the clamping-device is suspended, so that these cheeks, which are resilient, may spread sideways. By this means the lead 4''' now in an advanced position, is released. When the filling tube 11 and the clamping-device 12, 17 are guided back by the action of the spring 15, due to the spread condition of the cheeks 12 the lead 4''' is not guided back with them, but remains in its advanced position, being held back in the resilient point-opening 13. Only when the clamping-ring 18, carried along by the surface 17, strikes against the ring 16 and settles firmly upon the conical surface 17, is the lead again clamped. As a result the lead, which has been pushed forwards, remains partly in this forward position.

40 The above-described propelling mechanism is not the object of this invention. The propelling mechanism may be constructed in any manner desired.

This application is solely concerned with the 45 form of the magazine and of the devices for the guiding of the leads from the magazine into the filling tube.

To facilitate this guidance, according to Figs. 1 and 2 one or more resilient parts 21 are attached to the jacket 2, which extend into the inside of the magazine-case through slots 22 arranged within the same. When pressure is exercised upon the cap 7, the resilient parts 21, pass from the position shown in Fig. 1 into the position shown in Fig. 2, so that they do not move sideways. These movements are passed on to the store of leads 4 and loosen it in such a manner that the introduction of a new lead into the filling-tube 11 is thereby facilitated.

60 According to Figs. 3 and 4 the walls of the magazine 3 are provided with a slanting slot 23, into which enters a peg or projection 24 fastened either to the sleeve 2 or to the outer wall 1. The walls of the magazine 2 are also provided 65 with two or more projections or wings 25, 26, 27, directed inwardly. The width of these projections or wings may be suitably varied as required. When pressure is exercised on cap 7 by a magazine shaped as shown in Fig. 3, since the slot 23 must 70 slide alongside the peg 24, the magazine walls 3 turn with the cap 7. The turning of the magazine walls 3 is transmitted to the leads within the mechanism by the inwardly projecting wings 25, 26, 27, so that the former are brought into movement and loosened.

According to Figs. 5 and 6 the lead-bottom is attached to the filling-tube 11 and is divided by various slots 28, 29 etc. into separate tongues 30, 31 etc. The lead-bottom is held by the turned-over edge 32 of the sleeve 3, so that the different tongues 30, 31 etc. bend, for example tilt outwardly, when pushing the sleeve. A slight shaking of the store of leads, which facilitates the sliding of the lead into the filling-tube, is caused by this change of shape of the magazine bottom during the pushing of the cap and its drawing back.

Fig. 7 shows the lead-bottom according to Fig. 5 in the position into which it is brought by the pushing of the cap 7.

According to Fig. 8 the filling-tube 33 is not rigidly attached to the ring-body 34, which similarly to the ring-body 8 in Fig. 1 is firmly fastened to the magazine-walls 3. The filling-tube 33 is arranged movably in the ring-body 34. At the same time the outside of the filling-tube is provided with projections 35, 36, which during the backward—and forward—movement of the cap are engaged by corresponding projections 37, 38 of the ring-body 34. The upper part of the filling-tube 33 arranged movably approximately at the level of the magazine bottom is suitably formed shovel-shaped. The shovel-point 39, which extends slightly into the magazine-space 40, in order to keep back the leads on one side from the filling-tube, penetrates farther into the magazine-space 39 when the cap is pressed downwards. The shovel-point thus turns aside any leads blocking the point of entrance and facilitates the sliding of a single lead into the filling tube.

The form of the present invention may be altered in different ways within the scope of the main idea. In accordance with the invention the form of a magazine for automatic lead pencils, in which the forward movement of the cap is transmitted to the leads by the movement of some connecting organ, may be used in connection with any form of propelling mechanism. The magazine-bottom, the filling-tube and other details of the device may be formed as desired. It has been shown to be advantageous if the conical widening at the upper end of the filling tube measure only slightly less than twice the diameter of the leads. The passing-in of the leads is also facilitated by such form and measurement, since thus only one lead at a time can pass into the widening.

Having now particularly described and ascertained the nature of my said invention and in what manner the same is to be performed, I declare that what I claim is:—

1. A mechanical pencil of the type in which leads are fed in succession from a lead supply magazine, comprising a casing, a lead supply magazine mounted for reciprocation back and forth within said casing, means accessible from the exterior of said casing adjacent the rear end thereof for reciprocating said magazine within said casing, and means movable within said magazine and operated by movement of said magazine for disturbing the relative positions of various leads within said magazine.

2. A mechanical pencil of the type in which leads are fed in succession from a lead supply magazine, comprising a casing, a lead supply magazine mounted for reciprocation back and forth within said casing, means accessible from the exterior of said casing adjacent the rear end thereof for reciprocating said magazine within 7

said casing, a lead guiding tube operatively connected to said magazine to receive leads singly therefrom, and means for causing said tube, upon movement of said magazine, to move within said magazine to displace leads therein to facilitate the feeding of individual leads to said tube.

3. A mechanical pencil comprising a casing, lead feeding mechanism within said casing, a lead supply magazine mounted for movement back and forth within said casing, a cap at the rear end of said casing operatively connected to said magazine so that said magazine may be moved forwardly within said casing by pushing upon said cap, means connecting said magazine to said lead feeding mechanism to operate said mechanism to feed a lead forwardly upon forward movement of said magazine, and flexible means associated with said magazine and deformable upon movement of said magazine with said casing, for disturbing the relative positions of various leads within said magazine.

4. A mechanical pencil comprising a casing, lead feeding mechanism within said casing, a lead supply magazine mounted for movement back and forth within said casing, a cap at the rear end of said casing operatively connected to said magazine so that said magazine may be moved forwardly within said casing by pushing upon said cap, a lead guiding tube leading from said magazine to said lead feeding mechanism, and a loose connection between said guiding tube and said magazine so that when said cap and magazine are moved forwardly with respect to said casing, said tube may move into said magazine to disturb the relative positions of various leads therein.

5. A mechanical pencil comprising a casing, lead feeding mechanism within said casing, a lead supply magazine mounted for movement back and forth within said casing, said magazine having a forward end with an aperture therethrough, a cap accessible externally of said casing adjacent the rear end thereof and operatively connected to said magazine so that said magazine may be moved forwardly within said casing by pushing upon said cap, a lead guiding tube entering said aperture in said magazine and leading thence to said lead feeding means, said guiding

tube being movable longitudinally in said aperture, and stop means limiting the extent of longitudinal movement of said tube with respect to said magazine, so that upon movement of said magazine in a forward direction said magazine will first move forwardly with respect to said tube and the rear end of said tube will enter said magazine to displace leads therein, and continued forward movement of said magazine will carry said tube along with it.

6. A mechanical pencil comprising a casing, lead feeding mechanism within said casing, a lead supply magazine mounted for movement back and forth within said casing, said magazine having a forward end with an aperture therethrough, a cap accessible externally of said casing adjacent the rear end thereof and operatively connected to said magazine so that said magazine may be moved forwardly within said casing by pushing upon said cap, and a lead guiding tube longitudinally movable through a limited range in said aperture in said magazine and leading thence to said lead feeding means, said guiding tube being movable for a limited distance into said magazine upon forward movement of said magazine.

7. A construction according to claim 6, in which the end of said guiding tube movable into said magazine is provided with a rounded shovel-like point on one side.

8. A mechanical pencil comprising a casing, lead feeding mechanism within said casing, a lead supply magazine mounted for movement back and forth within said casing, a cap at the rear end of said casing operatively connected to said magazine so that said magazine may be moved forwardly within said casing by pushing upon said cap, means connecting said magazine to said lead feeding mechanism to operate said mechanism to feed a lead forwardly upon forward movement of said magazine, and means movable in the interior of said magazine and moved by movement of said magazine within said casing for disturbing the relative positions of various leads within said casing.

AUGUST LEISTENSCHNEIDER.
